UNITED STATES PATENT OFFICE.

CHARLES LATTA, OF ST. LOUIS, MISSOURI, ASSIGNOR OF ONE-HALF TO ALLEN THURMAN LATTA, OF ST. LOUIS, MISSOURI.

INTERNAL-COMBUSTION ENGINE.

Application filed February 11, 1922. Serial No. 535,669.

To all whom it may concern:

Be it known that I, CHARLES LATTA, a citizen of the United States, residing at the city of St. Louis and State of Missouri, have 5 invented a new and useful Internal-Combustion Engine, of which the following is a specification.

This invention relates to internal combustion engines, and has special reference to 10 an arrangement, construction and relationship of valves for controlling the intake and the exhaust.

An object of the invention is to provide 15 an internal combustion engine having slide valves for controlling the intake and the exhaust arranged in a novel relationship in order to obtain efficient operation.

Other objects will appear from the following description, reference being made to 20 the drawing in which—

Fig. 1 is a plan view showing the arrangement of a piston and the two cooperating slide valves for controlling the intake and the exhaust.

25 Fig. 2 is a vertical sectional view showing the positions of the two slide valves about the time the intake valve begins to open, which is also the position of the valves at about the time the exhaust valve begins to open, the two valves as shown in Fig. 2 moving in opposite directions.

Fig. 3 is a vertical sectional view on the line 3—3 of Fig. 1.

Fig. 4 is a view showing details of one of 35 the slide valves.

The engine has a number of working pistons 1 operating in cylinders 2, only one of such pistons and cylinders being shown. The piston 1 has the usual piston rod connection 3 with the crank shaft 4.

The engine has a number of working pistons 1 operating in cylinders 2, only one familiar manner so as to provide a space or chamber 6 above each piston when the piston is up. In such space or chamber the gas is compressed and exploded as an incident to the operation of the engine, each cylinder being provided with a spark plug 7 forming a part of an ignition system.

50 The casting in which the cylinders 2 are formed also contains the cylinders for the slide valves. There are two slide valve cylinders in the casting for each piston cylinder, the valve cylinder 8 containing the intake valve and the valve cylinder 9 con-

taining the exhaust valve. The head plate 5 extends over and covers the upper ends of the valve cylinders 8 and 9, leaving the compression and combustion space or chamber 6 at all times in direct communication with 60 the valve cylinders.

A sliding piston valve 10 is operatively mounted within the cylinder 8 and is connected with its cam 11 on the cam shaft 12 by a rod 13. A similar sliding piston valve 14 is operatively mounted in the cylinder 9 and is connected with its cam 15 on the shaft 12 by a rod 16.

An important feature in the relationship of the parts will be understood by reference 70 to Fig. 3. As there shown the cams for operating the piston slide valves for each cylinder of the engine have a novel relationship, the long radii of the two cams being at an angle of 90°, the long radius of the cam 11 75 for the intake valve being shown at IV and the long radius of the cam for the exhaust valve being shown at EV.

The port 17 shown in Fig. 3 shows the position of the intake port for admitting 80 gas into the cylinder 8; and also the position of the exhaust port for exhausting from the cylinder 9. The intake port to the cylinder 8 is in the same relative position as the exhaust port from the cylinder 9. Considering that the valve shown in Fig. 3 is the exhaust valve 14 it will be seen that said valve in the cycle of operation indicated by the arrows adjacent to the broken line gearing is moving upwardly to closed position and is 85 just closing the exhaust port. Obviously, then, the intake valve is moving downwardly to open position to permit gas to be drawn into the cylinder as an incident to the downward movement of the working piston 1 90 shown. In this way a proper relationship as between the valve devices and parts is maintained.

In Fig. 4 it will be seen that each of the 100 piston slide valves is equipped with a number of split expansion piston rings 18 for maintaining perfect seal as between the valves and the walls of the cylinders in which they operate. Looking at Fig. 3 it will be seen that the upper packing ring 18 is just contacting with the cylinder wall above the port 17. At the same time the upper packing ring on the intake valve is just leaving contact with the cylinder wall above the intake port. By the time any 105 110

- gas is drawn into the engine cylinder the exhaust valve packing ring 18 will be in position to seal the exhaust port perfectly, so that there is no escape or loss of live gas.
- 6 This operation is reversed when the engine exhausts. That is, the upper packing ring on the intake valve 10 seals the intake port at the same time that the upper packing ring on the exhaust valve opens the exhaust port, thereby preventing the exhaust from being forced into the intake manifold.

Each of the ports 17 has a width about equal to the diameter of the valve cylinder with which it communicates, while the 15 length of each of said ports axially of the valve cylinder is relatively narrow. Each port 17 is divided vertically by a partition 17a, the inner edge of which is continuous with the wall of the valve cylinder above 20 and below the port. Bearing for the packing rings on the valves is thereby provided midway between the side edges of each port, and the ends of the packing rings are prevented from becoming caught or fouled in 25 the ports. By this arrangement only a relatively short movement of each valve is required in order to open and to close the port controlled thereby.

The ratio of the gear wheel 19 on the crank 30 shaft to the gear wheel 20 with which it meshes on the cam shaft is one to two, making an engine of the four-cycle type.

Due to the relationship of the parts described explosion takes place during the 35 rapid and final portion of the downward movement of the exhaust valve. The main force of the explosion is imparted against the upper end of the working piston 1 and only the scattered force of the explosion affects the valves, with the result that the two 40 valves are about balanced when the explosion occurs.

I claim:

1. In an engine, a piston cylinder, a compression and combustion chamber at one end of the cylinder, separate inlet and exhaust valve cylinders having their upper ends in the same plane with and communicating with said chamber in the same plane, an inlet 45 port to the inlet valve cylinder, a sliding piston valve in said inlet valve cylinder, an exhaust port from said exhaust valve cylinder in the same plane with said inlet port, a sliding piston valve in said exhaust valve cylinder, a sealing device on each of said valves, said valves being duplicates, a cam 50 shaft, cams of equal size on said shaft having their long radii at an angle of 90° 55 relative to each other, and connections of equal length from said cams for operating said valves in strokes of equal length and in a relationship in which the sealing device on the inlet valve is beginning to open the inlet port when the sealing device on the exhaust valve has closed the exhaust port, and vice versa.

relative to each other, and connections of equal length from said cams for operating 60 said valves in strokes of equal length and in a relationship in which the sealing device on the inlet valve is beginning to open the inlet port when the sealing device on the exhaust valve has closed the exhaust port, 65 and vice versa.

2. In an engine, a working piston cylinder, a pair of valve cylinders having their upper ends in the same plane with each other and with the piston cylinder a compression 70 and combustion chamber extending across the upper ends of all of said cylinders, an inlet port opening into one of said valve cylinders, a sliding piston valve in the valve cylinder in which the inlet port opens, sealing devices on said valve arranged to seal the upper and lower parts of said port at one time, an exhaust port from the other valve cylinder in the same plane with said inlet port, a sliding piston valve in the cylinder 75 from which the exhaust port opens, said valves being duplicates, and sealing devices on said second piston valve arranged to seal the upper and lower parts of said exhaust port at the same time that said first-named sealing devices seal said inlet port as aforesaid.

3. In an engine, a working piston cylinder, a pair of valve cylinders having their upper ends in the same plane with each other 90 and with said piston cylinder, a combustion and compression chamber extending across the ends of all of said cylinders, an inlet port opening into one of said valve cylinders, a sliding valve on the valve cylinder in 95 which the inlet port opens, sealing means on said valve arranged to seal the top and bottom of said port at one time, an exhaust port from the other valve cylinder in the same plane with said inlet port, a sliding 100 piston valve in the cylinder from which the exhaust port opens, said valves being duplicates, sealing means on said second valve arranged to seal the top and bottom of said exhaust port at the same time that the first 105 named sealing means seal said inlet port as aforesaid, a cam shaft, cams of equal size on said shaft having their long radii at an angle of 90° relative to each other, and connections of equal length for operating said 110 valves in a relationship in which said sealing means on the inlet valve begins to open the inlet port when said sealing means on the exhaust valve has closed the exhaust port, and vice versa.

CHARLES LATTÀ.
